Inventor:
AUGUST BOUCHERY,
By his Attorney John C. Leifert

UNITED STATES PATENT OFFICE.

AUGUST BOUCHERY, OF NEW YORK, N. Y., ASSIGNOR, BY MESNE ASSIGNMENTS, TO WALLACE NOVELTY COMPANY, OF NEW YORK, N. Y., A CORPORATION OF NEW YORK.

SUCTION SUPPORTING DEVICE.

1,117,548.

Specification of Letters Patent. Patented Nov. 17, 1914.

Application filed February 21, 1914. Serial No. 820,157.

To all whom it may concern:

Be it known that I, AUGUST BOUCHERY, a citizen of the United States, residing in the borough of Brooklyn, in the county of 5 Kings, city and State of New York, have invented new and useful Improvements in Suction Supporting Devices, of which the following is a specification.

This invention relates to suction supporting devices particularly adapted for use in connection with the base of a portable support for an electric lamp, mirror or other object to support the same on a flat surface at an angle to the horizontal, such as a window pane or mirror of a dresser or the like, and it is the object of the invention to provide a suction supporting device of this character which is cheap and simple in construction and efficient in operation.

20 In carrying out the invention I provide a rigid hollow base by which the lamp or mirror is supported, a suction cup of suitable material, such as rubber, has a stem connected thereto whereby it is slidably supported in the base, and with which stem a spring coöperating tensioned to draw the suction cup into and maintain it within the base. A finger-piece secured to the stem of the suction cup extends through an opening in the lamp or mirror support to manipulate the suction cup to project it beyond the base against the tension of the spring to cause it to engage with the surface from which it is desired to sustain the lamp or mirror. The base when the pressure is released on said finger-piece due to the action of the spring firmly presses or bears against the surface from which the device is sustained preventing sagging of the lamp or mirror, and the pressure of the spring on the stem of the suction cup tends to increase the vacuum in the suction cup by exerting a pull thereon.

45 A further object of the invention is to adapt a suction device of this character to a portable electric lamp support in which a spool or reel upon which an electric current conductor is adapted to be wound is rotatably supported in a hollow base by a stem 50 fixed to and extending outward from the axle of the spool and which stem also serves as the support for the lamp or bulb.

In the drawing accompanying and forming a part of this specification, Figure 1 is a 55 sectional side elevation of a portable electric

lamp support or stand with an embodiment of my invention applied thereto showing the lamp support sustained by the suction cup from a glass surface which is perpendicular to the horizontal. Fig. 2 is a sectional side elevation similar to Fig. 1, but showing the manner of applying the suction device; and Fig. 3 is a plan view of a blank from which the finger-piece for the stem of the suction cup is formed.

60 Similar characters of reference designate like parts throughout the different views of the drawing.

In the drawing I have illustrated an embodiment of my invention in connection with a portable electric lamp support or stand, comprising a hollow base 4 open at the bottom with a nipple 5 projecting centrally from the top, and said nipple having an opening in the end. Seated in a recess 65 formed in the juncture of the base and nipple is a washer 6 the opening in which is of the same size as the opening in the end of the nipple for a purpose to be hereinafter described.

70 A spool or reel is inclosed by the base upon which to wind or coil a cable 7 containing the electric current conductors. This spool consists of a substantially flat side member 8 to lie contiguous to the inner face 75 of the top of the base, while the other side 9 is formed with a central recess 10 to constitute the core of the spool to which the spool end 8 is fixed. Fixed at one end to an opening in the spool core adjacent the side 80 8 is a tubular stem 11 to extend longitudinally from the axis of the spool, said stem passing through the openings in the washer 6 and the end of the nipple and fitting snugly 85 therein to rotatably support the spool by 90 said stem, the openings in the washer and the nipple providing a long bearing for such stem. Portions of the end of the stem are cut away to provide a pair of opposite yielding fingers. A socket 12 to removably carry 100 an electric lamp or bulb 13 is connected to the spool stem to swing on an axis transverse to the axis of the spool by a tubular coupling 14 secured thereto, said coupling having a pair of opposite fingers 15, 15 to 105 embrace the outside of the yielding stem-fingers and pivotally connected thereto by a screw 16 passing through openings in the coupling and stem fingers with a knurled nut 17 connected to the projecting threaded 110

end. Said screw also passes through a tubular member 18, the ends of which abut against the inner faces of the stem fingers. By tightening the nut 17 the coupling fingers 15 will bind against the stem fingers and thus frictionally maintain the lamp in any angular position relative to the base to which it may be adjusted. The spool stem is preferably stamped from a flat piece of metal and then formed tubular, and to prevent spreading of the stem fingers and to also prevent axial movement of the spool, I provide a binding collar or sleeve 19 outside of the support and confined between the nipple 5 and the ends of the coupling fingers 15.

As already stated the essential feature of the invention is to sustain a portable support or stand for a lamp, mirror or the like by means of a suction device from a smooth, non-porous surface 20 at an angle to the horizontal, such as a pane of glass, or the mirror of a dresser or the like. This suction device consists of a cup 21 of suitable material, such as rubber, connected to one end 25 of a stem 22 which may be molded directly in the material of the cup. This stem 22 is slidably supported in the base, in the present instance mounted in a support 23 in the form of a yoke fixed in the core of the spool 30 and extends into the spool stem 11. A finger-piece 24 has a screw threaded connection with the end of the stem of the suction cup, the free end of which finger-piece extends through an opening in the spool 35 stem formed by the cut-out portion between the spool-stem fingers, as clearly shown in Figs. 1 and 2. This stem is stamped from sheet metal into the form of the blank shown in Fig. 3, when the upper end is bent laterally and the lower end formed into a tube and internally screw threaded. The suction cup is normally drawn into and maintained in the spool core within the outer contour of the base 4, as shown in dotted lines in Fig. 2, by the tension of a spring 25 coiled 40 about the stem 22 and confined between the support 23 and the finger-piece 24. One end of the cable 7 containing the current conductors is passed through an opening 26 in the core of the spool and then passes up through the spool stem and hollow coupling 45 to contact terminals in the lamp socket 12. The other end of the cable passes through an opening in the base and has a plug 27 connected thereto.

The suction cup normally occupies the position shown in dotted lines in Fig. 2 due to the tension of the spring 25. Should it be desired to support the stand by means of the suction device the suction cup is projected out from the spool core and beyond the contour of the base by pressing on the finger piece 24, as shown in Fig. 2 in full lines, and the suction cup firmly pressed 55 against the surface from which it is desired

to sustain the device, as shown in Fig. 1. The finger piece is then released when the spring 25 will tend to draw the cup inward creating a vacuum in the suction cup and causing it to adhere to the surface with which it is in contact. The tension of the spring will also cause the base to firmly bear or press against the surface from which it is sustained, preventing sagging of the support or stand.

It is to be understood that the invention is not limited to the particular adaptation illustrated in the drawing; that is, to be used in connection with a lamp support or stand in which a reel or spool is utilized on which to wind the current conductors, since it could be used in various other forms of portable supporting devices.

Having thus described my invention, I claim:

1. The combination with a base having a stem centrally thereof to support a lamp or the like, of a suction cup; a stem to which the suction cup is connected slidably supported in the base and extending into the base stem and a portion extending through an opening in said stem; and a spring tensioned to draw said cup within the base; said suction cup adapted to be projected out from the base against the tension of the spring, substantially as and for the purpose specified.

2. In a portable support for a lamp or the like, the combination with a base having a stem central thereof to support a lamp or the like, of a suction cup; a stem to which the suction cup is connected slidably supported in the base and extending into the base stem; a spring coiled about and co-operating with the stem of the suction cup to normally maintain said cup within the base; and a finger-piece connected to the stem of the suction cup and extending through an opening in the base stem to project the suction cup out from the base against the tension of the spring.

3. In a portable support for a lamp and the like, the combination with a base having a central opening, of a spool having a hollow stem to engage in the base opening to rotatably support the spool therein and serve as the lamp supporting stem; a suction cup to normally engage in the spool core; a stem to which the cup is connected slidably supported in said spool stem and having a portion to project through an opening in said spool stem; and a spring co-operating with the stem of the suction cup to normally maintain the suction cup within the core of the spool.

4. In a portable support for a lamp and the like, the combination with a base having a central opening, of a spool having a hollow core and hollow stem projecting along its axis to engage in the base opening to

5 rotatably support the spool in the base, and said stem serving as the lamp supporting stem; a suction cup to normally engage in the spool core; a stem to which the cup is connected slidably supported in the spool stem; a spring coöperating with the stem of the suction cup to normally maintain the suction cup within the core of the spool; and a finger piece connected to the stem of

the suction cup and extending through an opening in the spool stem to project the suction cup out from the spool core and the base against the tension of the spring, substantially as and for the purpose specified.

AUGUST BOUCHERY.
